UNITED STATES PATENT OFFICE.

DAVID SHERWOOD KENNEDY, OF BROOKLYN, NEW YORK, ASSIGNOR TO MERGEN-
THALER LINOTYPE COMPANY, A CORPORATION OF NEW YORK.

TYPOGRAPHICAL MACHINE.

1,129,577.

Specification of Letters Patent. Patented Feb. 23, 1915.

Application filed October 27, 1914. Serial No. 868,793.

To all whom it may concern:

Be it known that I, DAVID SHERWOOD KENNEDY, a citizen of the United States, residing at Brooklyn, in the county of Kings 5 and State of New York, have invented certain new and useful Improvements in Typographical Machines, of which the following is a specification, reference being had therein to the accompanying drawing.

10 This invention relates to typographical machines, such as linotype machines of the general organization represented in Letters Patent of the United States No. 436,532, to O. Mergenthaler, wherein circulating matrices are stored in grooved magazines and released therefrom by suitable escapement devices in the order in which their characters are to appear in print and then assembled in line, the composed line transferred 15 to the face of a mold, the mold filled with molten metal to form a slug or linotype against the matrices which produce the type characters thereon, and the matrices thereafter returned through distributing mechanism to the magazines from which they 20 started.

More particularly, it relates to the construction of the magazines and specifically of the grooves therein, as will appear more 25 fully from the subsequent description and claims.

In the accompanying drawing, I have shown my invention only in preferred form and by way of example, and as applied to a 30 linotype machine, but obviously many changes and variations may be made therein, and in its mode of application, which will still be comprised within its spirit. Similarly, it may be adapted to other kinds of 35 typographical machines, such as typesetters, typecasters and the like, which handle type or dies, instead of matrices. Generally speaking, I desire it to be understood that I do not limit myself to any specific form or 40 embodiment, except in so far as such limitations are specified in the claims.

Referring to the drawing: Figure 1 is a 45 longitudinal section through the magazine and the adjacent parts of a linotype machine, with my improvements embodied therein; Fig. 2 is a perspective of a portion of the magazine, etc.; Fig. 3 is a section on the line 3—3 of Fig. 1; and Fig. 4 is a similar view of an arrangement now in use.

The matrices X are as usual stored in the 55 magazine A and are released therefrom by the escapements B and pass into the race-way C on their way to the other assembling devices, all in the ordinary manner. The escapements are actuated by the reeds D, 60 which in the form shown extend across the front of the magazine so that the matrices are forced to pass between them, in a manner similar to that presented in a number of commercial machines. The parts so 65 far described are or may be of any desired or improved construction, and in themselves constitute no part of my present invention, except as hereinafter specified.

In ordinary practice, the magazine is in 70 the shape of a trapezium, with its lower or delivering end parallel to its upper or receiving end, but of materially less extent, and with its two sides or edges downwardly converging. The channels therein are 75 constituted by opposing series of grooves in the upper and lower faces, wherein the matrix ears engage and travel, and because of the general contour of the magazine, these grooves also converge from the upper to the 80 lower end; and also in each pair, the lower groove has lain directly beneath the upper one, or in the same plane therewith. In the early form of magazine, it has been provided with top and bottom plates of the 85 same length, and consequently with a rectangular or squared end, so that the grooves in each pair are of the same length; but in magazines of the later type, the end of the magazine has been beveled or cut off at an 90 inclination, as shown in Fig. 1, and as a result the upper groove is materially shorter than the lower one. Due to the general convergence of the grooves, and also the fact that the upper one terminates in advance of 95 the lower one, the continued engagement of the matrix in the extended portion of the lower groove has the effect of delivering it between the escapement reeds out of parallelism therewith, and thus requiring an undue separation between them. The result of this old arrangement is indicated in Fig. 4, wherein the magazine A¹ is formed with the usual upper and lower grooves E¹ and F¹, and wherein due to the greater extent 100 of the grooves F¹, the matrices X¹ are delivered between the reeds D¹ out of parallelism therewith, or, as it appears in the

plane of section, tilted with respect thereto, and thus involving a material waste of space.

In order to correct the difficulty, and referring now to Figs. 1, 2 and 3, the grooves E and F in the upper and lower plates are relatively offset or staggered, as best shown by the heavy and light dotted lines in Fig. 2, the lower grooves F being no longer in the same plane with the upper grooves E, but slightly inclined therefrom to the right, with the effect that the engagement of the longer lower groove with the matrix tends to alter its relative position and to bring it into parallelism with the reeds as it passes between them. This result is best indicated in Fig. 3, in which, when compared with Fig. 4, it will be seen that the ends of the lower grooves have been effected shifted to the right in relation to the ends of the upper grooves, and so as to bring the matrices into parallelism with the reeds, as appears in the plane of section. In this manner, the waste of space is prevented, and as a result thereof either the reeds may be located nearer to each other in connection with the same width of matrix, or if they be located at the former distance from each other, there will be ample space for much thicker matrices to pass between them.

This construction corrects a difficulty long existent in connection with magazines provided with the earlier arrangement of grooves, and particularly adapts the magazine to modern conditions, wherein larger matrices are often employed, or where for other reasons it is desirable to avoid the waste of space.

As previously stated, I have shown my invention only in preferred form and by way of example, and as applied to a specific type of mechanism, but obviously many modifications and alterations therein, and in its mode of adaptation, will suggest themselves to those skilled in the art, without departure from its scope.

Having thus described my invention, its construction and mode of operation, what

I claim and desire to secure by Letters 50 Patent of the United States, is as follows:

1. A magazine for typographical machines formed with two opposing series of grooves, some of the grooves of one series being offset or staggered with relation to 55 the corresponding ones of the other series, for the purpose described.

2. A magazine for typographical machines beveled at its lower end and formed with two opposing series of grooves converging toward its lower end, some of the grooves of one series being staggered or offset with relation to the corresponding grooves of the other series.

3. A magazine for typographical machines 65 formed with two opposing series of grooves converging toward its lower end, the degree of convergence of one series of grooves being less than that of the other series.

4. In a typographical machine, the combination of a magazine beveled at its lower end and formed with two opposing series of grooves converging toward such end, and a series of escapement actuating devices extending across the beveled end of the magazine, the said magazine having some of the grooves of one series offset with relation to the corresponding grooves of the other series.

5. In a typographical machine, the combination of a magazine beveled at its lower end and having channels converging toward such end, and a series of escapement actuating devices extending across the beveled end 75 of the magazine, the said actuating devices and the magazine channels being relatively arranged so that the side faces of the type or matrices will lie parallel with the side faces of the actuating devices as they pass 80 therebetween.

In testimony whereof, I have affixed my signature in presence of two witnesses.

DAVID SHERWOOD KENNEDY.
